Primary Examiner—Louis S. Zarfas*Attorney, Agent, or Firm*—Sterne, Kessler, Goldstein & Fox[57] **CLAIM**

The ornamental design for a shoe closure, as shown and described.

DESCRIPTION

FIG. 1 is a left side elevational view of a shoe closure showing our new design;
FIG. 2 is a right side elevational view thereof;
FIG. 3 is a top plan view thereof;
FIG. 4 is a front elevational view thereof; and,
FIG. 5 is a perspective frontal elevational view thereof.
The broken line showing of a shoe in FIGS. 1-5, is environmental only and forms no part of the claimed design.
